United States Patent Office

Des. 188,608
Patented Aug. 16, 1960

188,608

CHEST

John J. Lubberts and Lambert J. Mulder, Grand Rapids, Mich., assignors to Tomlinson of High Point, High Point, N.C., a corporation of North Carolina

Filed July 30, 1959, Ser. No. 57,008

Term of patent 14 years

(Cl. D33—19)

The figure is a front perspective view of a chest showing our new design.

The side not shown is like the side shown while the back and top are plain and unornamented.

We claim:

The ornamental design for a chest, substantially as shown and described.
